UNITED STATES PATENT OFFICE

132,356

DESIGN FOR AN ELECTRIC PLATE HEATER

Halvdan J. Eriksen, Ottawa, Ontario, Canada

Application September 18, 1941, Serial No. 103,743
In Canada March 18, 1941

Term of patent 7 years

To all whom it may concern:

Be it known that I, Halvdan J. Eriksen, a citizen of Canada, residing at 238 Holmwood Avenue, in the city of Ottawa, Province of Ontario, Dominion of Canada, have invented a new, original, and ornamental Design for an Electric Plate Heater, of which the following is a specification, reference being had to the accompanying drawing, forming part thereof.

In the drawing:

Fig. 1 is a plan view of an electric plate heater showing my new design.

Fig. 2 is a side view of Fig. 1.

I claim:

The ornamental design for an electric plate heater, substantially as shown.

HALVDAN J. ERIKSEN.
